TALLOW COLOR STABILIZATION

Rex J. Sims, La Grange, and De Witte Nelson, Elmhurst, Ill., assignors to Swift & Company, Chicago, Ill., a corporation of Illinois

No Drawing. Application March 20, 1953,
Serial No. 343,758

3 Claims. (Cl. 260—398.5)

The present invention relates to color stabilization of fats. More specifically, the invention is directed to the stabilization of decolorized tallow against color reversion.

One of the major problems in the production of tallow is the control of color reversion tendencies exhibited by decolorized tallow. In the decolorization of tallow the tallow is normally treated with propane to remove color bodies. This treatment provides a desirable product with respect to color but does not provide a color-stable product. The decolorized tallow often exhibits color reversion tendencies and before it reaches the consumer it is too dark for use. Under storage conditions the tallow is normally subjected to elevated temperatures which are required to maintain the tallow in a fluidized condition. Tallow thus stored exhibits greater color reversion tendencies and the rate of darkening increases with increases in temperature.

Propane-decolorized, inedible tallow will sometimes darken to a color above soap manufacturers' specifications overnight. To overcome this problem, many approaches have been tried but with only partial success. It has been found that where decolorized oil is kept under relatively cool conditions, such as 140° F. when compared to 212° F., the oil does not darken as rapidly. It has also been determined that decolorized oil does not darken as rapidly if it is not stored in iron storage vessels. Comparative tests have shown that when stored in glass, the decolorized oil has a tendency to retain a bleached color more readily. Decolorized oil has also been stored under nitrogen, rather than in contact with air, with a certain amount of success. Moisture content has also been controlled with the result that partial stabilization is apparent.

Such known methods, however, have not produced adequate stabilization against color reversion to the point that the problem no longer is present.

It is, therefore, an object of the present invention to treat decolorized tallow in such a manner as to substantially overcome color reversion.

Other objects, not specifically set forth, will become apparent from the following detailed description.

Generally, the present invention comprises the addition of quantities of hexamethylenetetramine to decolorized tallow prior to the storage of the tallow. It has been found that small percentages of hexamethylenetetramine added to propane-decolorized tallow, while the tallow is still in a decolorized state, substantially prevents the color reversion which normally occurs when propane-decolorized tallow is stored under elevated temperatures. It is known that elevated temperatures promote color reversion, but due to the need for elevated temperatures during storage it has been found necessary to take steps to reduce color reversion while maintaining such conditions. The use of small percentages of hexamethylenetetramine as an additive to propane-decolorized tallow not only reduces the color reversion properties of the decolorized tallow under normal conditions, but also reduces the color reversion properties of the decolorized

2

tallow under commonly-practiced storage conditions wherein elevated temperatures are utilized.

The following examples are illustrative of the present invention and are not intended to be considered as limiting thereto:

Samples of 100 grams each of propane-decolorized tallow were stored in open jars at elevated temperatures. Color readings were taken daily based on the F. A. C. color index which is well known in the art. Separate samples 10 were treated with hexamethylenetetramine in amounts ranging from 0.01% additive to 1% additive. A control sample was left untreated for comparative purposes. The following comparative table was formed from F. A. C. 15 readings taken on each sample over extended time intervals.

Additive, percent by weight	F. A. C. Colors			
	Days at 140° F.			
	0	5	10	15
Control (No additive)	7	11	13	17
0.01% Hexamethylenetetramine	7	9	11	13
Control (No additive)	7	11	13	17
0.1% Hexamethylenetetramine	7	7	9	11
Days at 212° F.				
0	1	2		
Control (No additive)	5	21	25	
1% Hexamethylenetetramine	5	17	21	

In the above examples the changes in color were determined by use of the F. A. C. color index. This index is based on an arbitrary system of color standards which makes use of various colored solutions of inorganic salts. The different salt solutions are sealed in vials and 26 such vials are used to make up the index. Each is given an odd number and the entire set is divided into five series. Light-colored fats are graded by the colors included in the first series which contains numbers 1 to 9, inclusive. The second series contains numbers 11, 11A, 11B, and 11C which are used for very yellow fats. Numbers 13 to 19 make up the third series and are used in conjunction with dark, reddish fats. The fourth series contains numbers 21 to 29 for greenish fats and the fifth series, for very dark fats, is made up of numbers 31 to 45. This 50 system is widely used in the art.

As can readily be seen from the above comparative results, the use of the color reversion inhibitor of the present invention substantially reduces color reversion in decolorized tallow. Such results are highly desirable from the standpoint of producing a stabilized product. The amounts of agent added may differ substantially depending on the storage time contemplated. However, there are practical limits as to the amount of additive used. This practical range exists from 0.01% by weight additive to 1% by weight additive. It is considered uneconomical to go above the 1% limit while it is not believed that sufficient additive would be present if less than 0.01% were utilized.

Along with the use of the additives of the present invention other well-known practices may be followed. Small percentages of citric acid may be added where the fat is to be stored in contact with carbon steel. Citric acid is well-known as a metal scavenger and, as such, helps in maintaining fat in a decolorized state under such conditions. In addition to the additives of the present invention, iron storage vessels, glass storage vessels, storage under nitrogen or moisture control methods may be used.

These different methods may be used collectively or in any combination desirable along with one of the additives of the present invention.

Obviously, many modifications and variations of the invention as hereinbefore set forth may be made without departing from the spirit and scope thereof, and therefore only such limitations should be imposed as are indicated in the appended claims.

We claim:

1. In the treatment of tallow the method of inhibiting color reversion which comprises: decolorizing said tallow with propane and immediately thereafter adding to said tallow relatively small quantities of hexamethylenetetramine.
2. In the treatment of tallow the method of inhibiting color reversion which comprises: decolorizing said tallow with propane and immediately thereafter adding to said

5 tallow at least 0.01% by weight of hexamethylenetetramine.

3. In the treatment of tallow the method of inhibiting color reversion which comprises: decolorizing said tallow with propane and immediately thereafter adding to said tallow quantities ranging from 0.01% to 1.0% by weight of hexamethylenetetramine.
